UNITED STATES PATENT OFFICE.

LOUIS DE ROQUEFEUIL, OF ASNIERES, FRANCE.

DESIGN FOR A BOTTLE.

Application filed January 29, 1926. Serial No. 16,320. Term of patent $3\frac{1}{2}$ years.

To all whom it may concern:

Be it known that I, LOUIS DE ROQUEFEUIL, a citizen of the Republic of France, residing at Asnieres, Seine, France, have invented a new and ornamental Design for a Bottle, of which the following is a specification, reference being had to the accompanying drawing, forming a part thereof.

In the drawing:

I claim:

The ornamental design for a bottle as

L. DE ROQUEFEUIL.
